CONTAINER LIFTER

Reed S. Harris, San Francisco, Calif., assignor
to Oswego Falls Corporation, Fulton, N. Y., a
corporation of New York

Application April 7, 1937, Serial No. 135,538

2 Claims. (Cl. 294—28)

This invention relates to container lifters and more particularly to a lifter for large paper containers used to package bulk ice-cream.

The invention has as an object a lifter of the type referred to embodying a particularly simple and economical construction by which the lifter may be used to conveniently lift and carry containers singularly, or in pairs.

The invention consists in the novel features and in the combinations and constructions hereinafter set forth and claimed.

In describing this invention, reference is had to the accompanying drawing in which like characters designate corresponding parts in all the views.

Figure 1 is a side, elevational view of a lifter embodying my invention, being partly in section and including contiguous portions of a pair of containers, the lifter being shown in applying position.

Figure 2 is a view, similar to Figure 1, with the lifter shown in gripping position.

Figure 3 is an end elevation of the lifter.

Figure 4 is a sectional view taken on lines 4—4, 25 Figure 3, and including contiguous side wall portions of a pair of containers.

The invention consists generally of a pair of opposed jaw members pivotally joined together and having arm portions extending at an angle 30 to the jaws and diverging upwardly from the pivot, a plate movably mounted on said pivot and depending between said jaws, and a handle member pivotally connected at its ends to the ends of said arm portions and being operable 35 upon movement toward and from said pivot to effect movement of the jaws toward and from said plate.

As here shown, the jaws 10 are pivotally joined together on a rivet or pin 11 and include integral 40 arm portions 12 which extend at an angle of approximately forty-five degrees to the opposed surfaces of the jaws 10, and diverging upwardly as illustrated in Figures 1 and 2 to form a tong construction. Links 13 are pivotally connected at like ends to the ends of the arms 12 as at 14, and the opposite ends of the links 13 are pivotally connected to the ends of a tubular handle member 15, the end portions 16 of which are flattened to form a slot to receive the inner ends of the 45 links 13. From the description thus far, it will be evident that movement of the handle member 15 toward and from the pivot 11 effects movement of the jaws 10 toward and from each other.

The construction further includes a plate 17 50 movably mounted upon the pivot 11, and is here

shown as comprising a pair of flat members 18 joined together at their lower end as by a rivet 19, and being formed at their upper ends with projections 20 bent over to form hinge eyes 21 to receive the pivot 11, the hinge eyes 21 being spaced apart sufficiently to receive the pivotal portion of the jaws 10, and also an operating member 22 movably mounted on the pivot 11 and arranged between the jaw members 10. The lower end of the operating member 22 is bifurcated 5 to receive the upper marginal edge of the members 20, and the upper end of the member 22 is formed with a finger hold 23.

The purpose of the plate is to provide a backing or supporting surface for the outside of the 15 container barrel, particularly when two containers are lifted and carried simultaneously. The function of the operating member 22 is to effect movement of the plate about the pivot 11 so that the user may conveniently shift the plate to central position between the jaws 10 preparatory to applying the device to the containers. The members 18 are concaved on their surfaces confronting the jaws 10 to better conform with the cylindrical body walls 25 of the containers, as shown 20 in Figure 4, and are provided with one or more protrusions 26 which bite into the outer surface 25 of the container wall to effect a more firm grip on the container.

In use, the handle member 15 is grasped in 30 the hand and one of the fingers inserted through the hole 23 in operating member 22 which permits convenient movement of the handle member 15 toward the pivot 11. The member 22 is then shifted about the pivot 11 to arrange the 35 plate 17 midway between the open jaws 10, and while in this condition the lifter is applied to the containers by inserting the presser plate between the containers and forcing the sharpened ends 27 of the jaws 10 through the covers of the 40 container. The operating member 22 is released and upon upward or lifting movement on the handle 15, the jaws 10 are moved about the pivot against the inner surface of the container barrels and each container barrel is thus gripped 45 between one of the jaws 10 and the plate 17. The device is readily removed from the containers by inserting the finger through the hole 23 of member 22 and effecting movement of the handle 15 toward the pivot 11.

The arrangement of the links 13 and handle member 15 is such that the ends of the handle member 15 coact with the arms 12 to form a stop for movement of the handle 15 toward the pivot 11, as illustrated in Figure 1.

It will be observed that the lifter described is of particularly economical and simple construction, being formed substantially from metal stampings, and the construction is such that the lifter is readily operated by one hand, permitting four containers to be lifted and carried conveniently at one time, or permitting the user to carry two containers leaving his other hand free to open doors, remove cabinet closures, etc.

10 What I claim is:

1. A container lifter comprising a pair of opposed jaws pivotally joined together and having arm portions diverging upwardly from said pivot point, a handle member pivotally secured to the outer ends of said arms and being operable upon movement toward and from said pivot to effect movement of said jaws about said pivot, a plate member movably mounted on said pivot and depending between said jaws, a plate operating member movably mounted on said pivot and extending upwardly from the pivot between the arm portions of the jaws toward the handle member, and being provided at its upper end with a finger

receiving aperture, said operating member being cooperable at its lower end with said plate to effect movement of the same about the pivot independently of the jaws.

2. A container lifter comprising a pair of opposed jaws pivotally joined together and having arm portions diverging upwardly from said pivot point, a handle member pivotally secured to the outer ends of said arms and being operable upon movement toward and from said pivot to effect movement of said jaws about said pivot, a plate member movably mounted at its upped edge on said pivot and depending between said jaws, a plate operating member movably mounted on said pivot and extending upwardly from the pivot between the arm portions of the jaws toward the handle member and being formed at its upper end with a finger receiving aperture, the lower end of said operating member being formed with a projection extending on each side of the plate, whereby said plate may be moved about said pivot upon movement of said operating member.

REED S. HARRIS.
